CLAIM

The ornamental design for an endoscope connector, as shown and described.

DESCRIPTION

FIG. 1 is a top, front and left side perspective view of an endoscope connector showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a top, front and left side perspective view thereof, shown in a state of use;

FIG. 9 is a top, rear and left side perspective view thereof, shown in a state of use; and,

FIG. 10 is a top, front and left side perspective view thereof, shown with the cap attached.

The broken lines depicting a cap, an ultrasonic controller connector and other medical equipment are for the purpose of illustrating environmental subject matter and form no part of the claimed design. The remaining broken lines depict portions of the endoscope connector that form no part of the claimed design.

1 Claim, 9 Drawing Sheets
